UNITED STATES PATENT OFFICE.

GEORGE A. HUEWE, OF CINCINNATI, OHIO, ASSIGNOR TO THOMAS C. BRADFORD, OF SAME PLACE.

EAR-PIECE FOR TELEPHONES.

SPECIFICATION forming part of Letters Patent No. 367,004, dated July 19, 1887.

Application filed January 15, 1887. Serial No. 224,413. (No model.)

To all whom it may concern:

Be it known that I, GEORGE A. HUEWE, a resident of the city of Cincinnati, in the county of Hamilton and State of Ohio, have invented 5 certain new and useful Improvements in Ear-Pieces or Attachments for Telephones, of which the following is a specification.

The object of my invention is to provide an ear-piece of novel construction for ready attachment to the ordinary telephone-receiver, and which shall form a comfortable cushion against the head, and at the same time completely surround the ear and cut off external sounds.

15 The various features of my invention and the advantages arising from their use conjointly or otherwise will be apparent from the following description.

In the accompanying drawings, Figure 1 is a 20 view in perspective of my ear-piece or attachment and a telephone-receiver, the attachment being applied to the receiver. Fig. 2 is a side elevation of the attachment apart from the receiver and provided with a stiffening-ring.

25 Fig. 3 is a view of the forward or receiving end of the receiver and the ear-piece or attachment applied thereto, the attachment and that portion of the receiver to which the attachment is applied being shown in section, 30 the section being a longitudinal central one, the remainder of the receiver being in elevation. Fig. 4 is a central section of the attachment from front to rear, the section being taken at the line $x-x$ of Fig. 2. Fig. 5 is a

35 view in perspective of the preferred form of ring which may, when desired, be employed to stiffen a portion of the said ear-piece or attachment. Figs. 6 and 7 illustrate modifications of the invention.

40 The device, as shown in Figs. 2 and 4, is made of a flexible elastic substance, preferably rubber. Its general shape is that of a hollow frustum of a cone. While said device is made in a single piece, it is convenient for purposes

45 of description to divide it into the ear-tube A and the curtain B. The ear-tube A terminates within in the annular ridge or shoulder a , and on the outside is provided with two flanges, a' , forming between them a groove, C. One 50 of these flanges, especially the lower flange, a' ,

may be omitted, but both flanges are preferably employed.

The device is applied to the telephone-receiver as shown in Figs. 1 and 3.

The curtain B is stretched over the end of 55 the receiver and the device pulled on until the shoulder a rests on the flange or head D of the receiver. On being released the curtain clasps the head of the receiver quite snugly, its elasticity enabling it to adapt itself to the 60 head, as shown most fully in Fig. 3. When in position on the receiver, the free end of the curtain fits under the shoulder or head D and serves to hold the device in position. To hold the ear-tube A in shape, and to prevent its slipping down over the head D, I sometimes employ the ring E, which is preferably but slightly elastic and made of a material stiffer than the rubber, the preferred material being metal, such as spring-brass. This ring E is 70 slipped over the ear-tube A and fits in the groove C. Instead of thus holding the ring E to place by means of one or both of the flanges a' , the ring may lie in the material of the ear tube or piece A and appear at the 75 surface of the latter, or be located in the interior thereof, these modifications being illustrated in Figs. 6 and 7. In such event the flanges a' may be omitted. An annular flange or flanges, as a' or a'' , if sufficiently 80 large, will operate to stiffen the ear-tube to the desired degree.

The device applied to a telephone-receiver greatly increases the efficiency of the latter, because it completely surrounds the ear when 85 in use and cuts off extraneous sounds. Moreover, it forms a cushion for the head, which cushion is much more comfortable than the ordinary telephone-receiver. In addition, the device commends itself on account of its simplicity and ease of application.

I do not in this case claim anything claimed in another pending application, No. 223,269, filed by me January 3, 1887.

What I claim as new and of my invention, 95 and desire to secure by Letters Patent, is—

1. The combination of the ear-tube A, having shoulder a , and elastic curtain B, adapted to clasp and overlap the end of the receiver, substantially as and for the purposes specified. 100

2. The combination of the ear-tube A, elastic curtain B, and ring E, substantially as and for the purposes specified.	5. As an attachment for a telephone receiver, the combination of the ear-tube A and the curtain B, made in one piece of elastic material, and the stiffening-ring C, substantially as and for the purposes set forth.
3. The combination of the ear-tube A, having flanges a' a'' , curtain B, and ring E, substantially as and for the purposes specified.	
4. The combination of the ear-tube A, having shoulder a and flanges a' a'' , curtain B, and ring E, substantially as and for the purposes specified.	

GEORGE A. HUEWE.
